UNITED STATES PATENT OFFICE.

WILLIAM WESLEY COOPER, OF FORTYFORT, PENNSYLVANIA.

COAL-WASHING MACHINE.

1,121,715.

Specification of Letters Patent. Patented Dec. 22, 1914.

Application filed September 8, 1914. Serial No. 860,655.

To all whom it may concern:

Be it known that I, WILLIAM WESLEY COOPER, citizen of the United States, residing at Fortyfour, in the county of Luzerne and State of Pennsylvania, have invented certain new and useful Improvements in Coal-Washing Machines; and I do declare the following to be a full, clear, and exact description of the invention, such as will enable others skilled in the art to which it appertains to make and use the same.

My invention relates to improvements in machines for washing coal and separating the same from rock and slate by specific gravity.

Heretofore, it has been common construction to provide a washing receptacle having a coal discharge opening at a comparatively high point and a rock and slate discharge opening at a relatively low point. The latter opening is usually normally closed by a manually operable gate. This construction has numerous disadvantageous features to overcome which I have primarily designed the construction to be hereinafter described.

One of the main difficulties with machines of the type above mentioned, is the fact that the slate or rock is prone to rise within the washing receptacle to such an extent as to allow a portion thereof to be discharged with the washed coal and, on the other hand, should but a small quantity of slate or rock accumulate, certain amounts of coal will invariably be discharged through the slate and rock outlet. In order to overcome these undesirable features, I have provided the construction herein described and claimed as shown in the drawings wherein:

Figure 1 is a vertical longitudinal section through a coal washing machine illustrating the application of my invention thereto; Fig. 2 is a vertical section as seen on the line 2—2 of Fig. 1; Fig. 3 is a horizontal section taken on the line 3—3 of Fig. 1; and Fig. 4 is a vertical transverse section taken on the line 4—4 of Fig. 1.

In the accompanying drawings, I have shown a coal washing machine comprising an upright tank 1 having a transverse partition 2 in its upper portion, the lower end of the tank 1 being suitably shaped to guide the material therein into a valved discharge pipe 3. To one side of the partition 2, a plunger 4 is provided which is here shown as carried by upright connecting rods 5

which are reciprocated vertically by eccentrics 6 mounted on a driven shaft 7. The action of this plunger is to force a quantity of water placed in the tank 1 upwardly and downwardly through a grate 8 one of whose edges is supported by the lower end of the partition 2 while its opposite edge is supported at 9 near the upper end of a comparatively short side wall 10 which is located directly opposite the side wall against which the plunger 4 reciprocates. As is common with devices of this character, the grate 8 inclines downwardly from its inner to its outer end thereby facilitating the discharge of rock or slate through a transverse opening 11 formed in the wall 10 above said grate, a suitably constructed carrier 12 being provided for the purpose of conveying the rock and slate, discharged through the opening 11, to a remote point.

By reference more particularly to Fig. 1, it will be seen that the wall 10 terminates at a suitable distance above the opening 11 and that a conveying trough 13 is continued from the casing 2 at this point, an endless carrier 14 being provided in the trough 13 for the purpose of conveying washed coal from the tank 2 in a manner to be described. It will likewise be noted that a second grate 15 is provided whose outer edge is located in contact with the upper end of the wall 10, said grate inclining downwardly and inwardly from its point of contact with said wall and terminating a suitable distance 90 above the grate 8.

Suspended upon a pair of hinges 16 one leaf of each of which is secured to the wall 10, is a transversely elongated rectangular door 17 which is located in and substantially closes the opening 11 under normal conditions, said door being provided with an inwardly and upwardly extending operating arm 18 to whose upper end an upright operating link 19 is pivoted, said link rising through an opening 20 in the grate 15 and being pivoted at 21 to a first class lever 22 which is fulcrumed in a fork 23 which rises from the top of the tank 1, a weight 24 being provided on the free end 105 of the lever 22 whereby to normally close the door 17 through the instrumentality of the rod or link 19, it being understood that said door is designed to swing outwardly.

With the parts as above described the 110 operation of the device is as follows: The newly mined coal, with a considerable

amount of rock and slate mixed therewith, is fed into the tank 1 above the grate 8, the amount entering the tank being controlled by the usual regulating gate 26. The 5 plunger 4 is now reciprocated through the means before described, this reciprocation forcing the water within the tank 1 upwardly and downwardly through the grate 8 and thereby separating the comparatively 10 light particles of coal from the proportionately heavy slate and rock, the coal now rising in the water to an extent sufficiently to be removed by the conveyor 14. In the meantime, the numerous small particles 15 of slate and rock are discharged either through the grate 8 or through the space surrounding the door 17. It will be understood, however, that since the larger particles cannot be discharged in this manner, 20 that these last mentioned particles will accumulate upon the grate 8. When the weight of the accumulated rock and slate is sufficient to overcome the weight 24, the door 17 will be forced outwardly thereby 25 discharging an amount of material into a trough 12 in which the endless conveyor 12 operates. It will therefore be seen that the provision of the automatically opened door or gate 17 prevents the rock and slate 30 from accumulating to an extent sufficient to allow the same to be discharged through the coal outlet. Furthermore, should any comparatively light rock or slate rise with the coal, the former will contact with the 35 inclined shield 15 before passing into the trough 13. The upward pressure of water directly above the grate 15 is considerably less than the pressure above the uncovered portion of the grate 8, this being caused by 40 the fact that the water must be forced through two grates at this point. The result is that the particles of rock will fall downwardly upon the inclined grate 15 and will again be positioned in the lower 45 end of the washing receptacle.

In addition to the above set forth use of the grate 15, the same acts as an efficient guard or shield for the pivotal connection between the link 19 and the arm 18.

50 From the foregoing description, taken in connection with the accompanying drawing, it will be seen that an extremely simple

structure has been provided for the purpose of carrying out the objects of the invention and that this construction will be absolutely automatic in its operation.

Having thus described my invention what I claim as new and desire to secure by Letters-Patent is:

1. A machine of the class described, comprising a washing compartment having a rock discharge opening in one side wall at a comparatively low point, and a coal discharge at a relatively high point, a grate closing the lower end of the compartment and inclined downwardly and outwardly to the rock discharge opening, a second grate inclined in the opposite direction and having its upper edge adjacent the coal discharge, said grate extending across the washing compartment and having its lower edge spaced from the first mentioned grate, rock discharging means, and means for passing an intermittent current of water through both grates. 75

2. A machine of the class described, comprising a washing compartment having a rock discharge opening in one side wall at a comparatively low point, and a coal discharge at a relatively high point, a grate closing the lower end of the compartment and inclined downwardly and outwardly to the rock discharge opening, a second grate inclined in the opposite direction and having its upper edge adjacent the coal discharge, its lower edge being spaced from the first mentioned grate, an outwardly opening door for said rock discharge opening, said door being hinged at its upper edge, an angular operating arm extending inwardly from said door, an upright link pivoted to said arm and passing upwardly through said second grate, yielding means for normally raising said link to normally close the door, and means for intermittently passing a current of water through both grates. 85

In testimony whereof I have hereunto set my hand in presence of two subscribing witnesses.

WILLIAM WESLEY COOPER.
